UNITED STATES PATENT OFFICE.

OTTO L. MERTZ, OF CHICAGO, ILLINOIS, ASSIGNOR TO JULES HERBERT BENJAMIN, OF CHICAGO, ILLINOIS.

DESIGN FOR A PACKAGE-TIE.

56,016.

Specification for Design.

Patented Aug. 10, 1920.

Application filed April 19, 1920. Serial No. 375,172. Term of patent 14 years.

To all whom it may concern:

Be it known that I, Otto L. MERTZ, a citizen of the United States, residing at Chicago, in the county of Cook and State of Illinois, have invented a new, original, and ornamental Design for Package-Ties, (A,) of which the following is a specification, reference being had to the accompanying drawing, forming a part thereof.

Figure 1 is a plan view of a package tie designed in accordance with my invention;

Fig. 2 is an edge view; and,
Fig. 3 is an end view thereof.

I claim:

The ornamental design for a package tie, as shown.

OTTO L. MERTZ.
